UNITED STATES PATENT OFFICE.

HENRY V. A. PARSELL, JR., AND ARTHUR J. WEED, OF NEW YORK, N. Y.

DESIGN FOR AN ENGINE-FRAME.

SPECIFICATION forming part of Design No. 33,087, dated August 14, 1900.

Application filed June 21, 1900. Serial No. 21,108. Term of patent 7 years.

To all whom it may concern:

Be it known that we, HENRY V. A. PARSELL, Jr., and ARTHUR J. WEED, citizens of the United States, and residents of the city of New York, borough of Manhattan, in the county and State of New York, have invented and produced a new and original Design for an Engine-Frame, of which the following is a full, clear, and exact description.

o The leading feature of our design consists in an engine-frame having a base with upwardly-tapering pyramidal bodies at each end and a depressed central portion, parallel longitudinal cylindrical rods extending from the top of one of said bodies to the other.

The design is illustrated in detail in the accompanying drawings, in which—

Figure 1 is a side elevation of an engine-frame embodying our design, and Fig. 2 is a

o plan thereof.

The frame comprises a rectangular prismatic base A, from each end of which rise pyramidal bodies B B', tapering upwardly,

the base A having a longitudinal depression A' between the two bodies B' and a depressed central portion A² between the bodies B B'. On top of said bodies B B' are horizontal plates C, with uprights D rising therefrom, and parallel longitudinal rods E extend from the uprights at one end of the base to those at the other end thereof. Between said rods are arranged circular bands F.

Having thus described our invention, we claim as new and desire to secure by Letters Patent—

The design for an engine-frame, as herein shown and described.

In testimony whereof we have signed our names to this specification in the presence of two subscribing witnesses.

HENRY V. A. PARSELL, JR.
ARTHUR J. WEED.
